[57] CLAIM

The ornamental design for a medical magnetic pad, substantially as is shown.

DESCRIPTION

FIG. 1 is a perspective view of a medical magnetic pad showing my new design;

FIG. 2 is a front elevational view of the pad shown in FIG. 1;

FIG. 3 is a rear elevational view thereof;

FIG. 4 is a top plan view thereof;

FIG. 5 is a right side view thereof; and

FIG. 6 is a cross-sectional view of the pad taken along line 6—6 of FIG. 2 in order to show a magnet embedded in one of circular parts attached to a support.
